(57) **CLAIM**

The ornamental design for a racquet for games, as shown and described.

DESCRIPTION

FIG. 1 is a left side view of a racquet for games, according to the novel design;

FIG. 2 is a front view thereof;

FIG. 3 is a right view thereof;

FIG. 4 is a back view thereof;

FIG. 5 is a top view thereof;

FIG. 6 is a front perspective view thereof; and,

FIG. 7 is a bottom view thereof.

The broken lines shown on the figures form no part of the claimed design.

1 Claim, 7 Drawing Sheets
